DESIGN FOR A COMBINED SERVING UTENSIL AND ASH TRAY

Charles Ralph Vigars, Bellflower, Calif.

Application December 29, 1945, Serial No. 125,142

Term of patent 14 years

(Cl. D85—2)

To all whom it may concern:

Be it known that I, Charles Ralph Vigars, a citizen of the United States and a resident of Bellflower, in the county of Los Angeles and State of California, have invented a new, original, and ornamental Design for a Combined Serving Utensil and Ash Tray, of which the following is a specification, reference being had to the accompanying drawing, forming part thereof, in which:

Figure 1 is a perspective view of a combined serving utensil and ash tray showing my new design.

Figure 2 is a top plan view thereof, and
Figure 3 is a side elevational view thereof.

I claim:

The ornamental design for a combined serving utensil and ash tray, substantially as shown.
CHARLES RALPH VIGARS.
